Des. 225,139
Patented Nov. 21, 1972

225,139

GLOVE

Raymond M. Vennetilli, 62 Rue Auguste Delaunne,
Villejuif, France

Filed Dec. 4, 1970, Ser. No. 26,285

Claims priority, application France Oct. 19, 1970

Term of patent 14 years

Int. Cl. D2—06

U.S. Cl. D2—372

FIG. 1

FIG. 2

FIG. 3

FIG. 1 is a perspective view of a glove showing my new design,

FIG. 2 is an enlarged fragmentary view of a portion thereof showing the flower-like design in enlarged perspective detail, and

FIG. 3 is a sectional view taken along the lower edge of the enlarged fragmentary portion shown in FIG. 2.

The other side of the glove is a mirror image of the side shown.

I claim:

The ornamental design for a glove, substantially as shown and described.
